UNITED STATES PATENT OFFICE.

WILLIAM U. FAIRBAIRN, OF BOSTON, MASSACHUSETTS.

GRATE-BAR.

SPECIFICATION forming part of Letters Patent No. 241,639, dated May 17, 1881.

Application filed March 21, 1881. (No model.)

To all whom it may concern:

Be it known that I, WILLIAM U. FAIRBAIRN, of Boston, in the county of Suffolk and State of Massachusetts, have invented certain new and useful Improvements in Grate-Bars, of which the following is a full, clear, and accurate description, reference being had to the accompanying drawings, forming a part of this specification in explaining its nature, in which—

10 Figure 1 is a perspective of a grate-bar illustrating my invention, with a portion of its web broken out to show the interior of the bar. Fig. 2 is a front elevation. Fig. 3 is a view in perspective, enlarged, of the rear part of the bar. 15 Figs. 4 and 5 are views representing a modification in construction, hereinafter more fully described.

This invention is an improvement upon that described in my application for Letters Patent 20 filed August 7, 1880. In that application I have described a grate-bar having end supports for suspending it in the furnace, and a hollow web within and below said supports, having an opening at its front end, which is some little 25 distance back from the front end of the bar, being closed at its rear and opening on one or both sides near the rear, whereby air may be drawn from the ash-pit through the bar by the action of the fire to the rear of the fire, thereby 30 providing for a sufficient supply of oxygen to properly support the combustion at that part of the furnace.

I have found in the practical working of my invention that owing to the rapidity with 35 which the air is drawn through the bar in some instances it is desirable to check its flow some during its passage through the bar, as by so doing the air is more heated in passing through the bar than otherwise would be the case. 40 I have also found that it is advantageous to build a narrow hood or projection over the exits to prevent ashes from falling into and clogging them or the passage within the bar, also to extend the mouth or opening to the passage to the end of the bar.

45 A is the bar. It has a fire-supporting surface, a , the end supports, a' , the web a^2 within and below the end supports, and the passage a^3 in the web, having an opening, a^4 , extending from 50 the bottom of the web upwardly and outwardly to the end of the bar, forming the narrow pas-

sage a^5 in the front end support. The web is closed at its rear end, and has one or more openings, a^6 , in one or both sides, at or near the rear and near the fire-supporting surface. 55

a^7 is a hood or projecting portion of the bar over each exit, preferably of the same length, and slanting outwardly and downwardly from the fire-supporting surface, so as not to increase its width materially, while it acts as a fender 60 in preventing ashes from lodging in the exit-passage.

a^8 are lugs, which project horizontally from the bar and serve to maintain it in position in relation to its companion bars by coming in 65 contact with the like lugs thereon.

To check the flow of air through the passage a^3 , and thereby to heat it, a number of devices can be employed, and among them I mention the use of asbestos or other non-combustible 70 material packed lightly in the passage, through which, however, air can be drawn. Wire-gauze, in one or more layers extending from side to side of the bar to retard the passage of air, will answer the purposes of this portion of the invention, or a central plate or partition for diminishing the volume of air by decreasing the size of the passage will perform the same effect. By this construction the air is not only retarded, but heated more readily, on account 75 of its volume being thin and the heat-radiating surfaces of the bar being increased.

One form of the partition-bar is shown in Fig. 4, the partition-plate being cast with the remainder of the bar. The division-plate, however, may be made separate and inserted into a groove in the bar, as shown in Fig. 5. Any other suitable means for accomplishing this device may be employed. 85

It will be observed—that is, in my invention 90 already described—the web is practically suspended in the ash-pit chamber, so that the passage therein is most advantageously located for receiving air, and that, also, the location of the mouth of the passage in the ash-pit is that 95 best adapted for the purpose, being arranged, when the bar is in position in the furnace, across the line of the principal part of the current of air from the ash-pit door to the fire.

Having thus fully described my invention, I 100 claim and desire to secure by Letters Patent of the United States—

1. In a grate-bar having a web, a^2 , provided with a passage, a^3 , through which air may be drawn, and having one or more exits, a^6 , upon one or both sides of the web, one or more hoods or projections, a^7 , in combination with said exit or exits, all substantially as and for the purposes described.

2. In a grate-bar having a passage in its web, through which air may be drawn, having an opening at the front end of the bar, and upon

one or both sides near the rear, the combination of such passage with means, substantially as described, for checking or retarding the flow of air in said passage, all as and for the purposes described.

WM. U. FAIRBAIRN.
